UNITED STATES PATENT OFFICE.

EDWIN M. ROSENBLUTH, OF PHILADELPHIA, PENNSYLVANIA.

DESIGN FOR A MEMBER FOR LAMP-BRACKETS.

SPECIFICATION forming part of Design No. 32,850, dated June 19, 1900.

Application filed May 21, 1900. Serial No. 17,484. Term of patent 14 years.

To all whom it may concern:

Be it known that I, EDWIN M. ROSENBLUTH, of Philadelphia, in the State of Pennsylvania, have invented and produced a new and useful Design for a Member of a Lamp-Bracket, whereof the following is a specification, reference being had to the accompanying drawings.

My invention is peculiarly applicable to a bracket arranged to be secured upon a vehicle-frame to support a lamp or other device in detachable relation therewith.

Figure 1 is a top plan view of a bracket member conveniently embodying my new design. Fig. 2 is a side elevation of the bracket member shown in Fig. 1; and Fig. 3 is a sec-

tional view of said bracket member, taken on the line 3 3 in Fig. 2.

The material feature of my design consists in the bracket-body A, having channel-flanges ²⁰ a intermediate of its length and provided at one extremity with a tubular extension B and at the other extremity with the hook or jaw C.

Having described my invention, what I claim as new, and desire to secure by Letters ²⁵ Patent, is—

The design for a member of a lamp-bracket as herein shown and described.

EDWIN M. ROSENBLUTH.
